UNITED STATES PATENT OFFICE.

FREDERICK W. EAMES, OF WATERTOWN, NEW YORK.

AIR-EJECTOR.

SPECIFICATION forming part of Letters Patent No. 241,331, dated May 10, 1881.

Application filed October 29, 1880. (No model.) Patented in England January 20, 1879.

To all whom it may concern:

Be it known that I, FREDERICK W. EAMES, a citizen of the United States, residing at Watertown, in the county of Jefferson and State of New York, have invented certain new and useful Improvements in Air-Ejectors, (Case I;) and I do hereby declare the following to be a full, clear, and exact description of the invention, such as will enable others skilled in the art to 5
10 which it appertains to make and use the same, reference being had to the accompanying drawings, and to letters or figures of reference marked thereon, which form a part of this specification, the same having been patented to me 15 by the government of Great Britain by Letters Patent No. 225, dated January 20, 1879.

Figure 1 represents a front elevation of an ejector to which my improvements have been applied. Fig. 2 represents a side elevation 20 of the same, and Fig. 3 a top-plan view of the same. Figs. 4 and 5 represent, respectively, a face and vertical sectional view of the gage for indicating the pressures in the brake-pipes. Fig. 6 represents a modified form of 25 gage.

My invention relates to air-ejectors for vacuum-brakes.

My present invention consists in a novel construction and arrangement of two ejectors of 30 different comparative capacities and two lines of brake-pipes connected therewith, the smaller ejector having communication with but one line of pipes, and the larger ejector so arranged as to have communication with one or both 35 lines of pipes.

It further consists in providing the controlling steam-valve of the larger ejector with a device consisting of a system of levers and a spring (or equivalent) and diaphragm acting 40 in opposition to each other, the diaphragm being connected by a pipe to the brake-pipe of the smaller ejector, whereby upon air being admitted to said brake-pipe it will cause the steam-valve of the larger ejector to be turned 45 on automatically.

In the drawings, A represents the larger ejector, and B the smaller. The construction of the ejector device proper of both are substantially alike, the parts differing only in regard to their size. They are fitted to the boiler in any known and suitable way, and with which

they communicate by the steam-pipe a. The construction of each of the ejectors is well known, my present invention being in constructing them of comparative different sizes 55 and capacities in connection with a double line of brake-pipes and valve apparatus, whereby a vacuum is automatically maintained in one line of pipes, B', by the continuous action of the smaller ejector B, and upon the reduction of the vacuum-pressure in said pipe a vacuum is created in the pipe A' and the steam-valve of the larger ejector turned on, so as to re-enforce the vacuum thus established in said brake-pipe A', thereby applying the brakes. 60 It should be understood, however, that ordinarily the brakes are put on by creating a vacuum in the brake-pipe A' by means of the ejector A independently of the use of the brake-pipe B' and its ejector B, the pipe B' and its 65 attached automatically-operating device for opening the steam-valve of the larger ejector A serving only where a more effective and instantaneous application of the brakes is required, as in cases of emergency. 70

A special description will be omitted of such parts of an ejector and brake apparatus as are old and not necessary to be here described.

The ejector A communicates with the brake-pipes A' and B', but the ejector B has connection with the brake-pipe B' only. 80

b' represents a valve, by means of which, if desired, communication between pipe B' and the ejector A may be cut off. Below this valve b' the pipe B' turns into a valve-box, b, which 85 is fitted with a stop-valve, c, the dropping of which onto its seat will prevent any air admitted into the pipe above the valve passing down along pipe B'. Below the stop-valve c the air-ejector B communicates with the brake-pipe B' by means of the pipe B², and by the continuous action of the ejector B, which is kept continuously blowing, a vacuum is maintained in the pipe B'. Below the point of connection of the pipe B² with the ejector B the 90 pipe is fitted with a valve, d, for admitting air thereto when the brakes are required to be put on in cases of emergency. This valve d is operated by the engine-driver. 95

The supply of steam to the ejector A is controlled by a valve mounted upon a vertical spindle, which carries at its upper end a hand- 100

lever, D. For the purpose of operating this apparatus automatically or without the assistance of the engineer, and at the same time without interfering with its proper manipulation by hand, I provide the handle D with a tail-piece extension, d'. From this tail end projects a pin, that enters and is free to play within a slotted horizontal link, e, which is jointed to the upper end of a vertical rock- 10 lever, f, having for its fulcrum a pin projecting from the ejector-casing. This lever receives through its shorter arm a tendency from a spring, g, to pull upon the link e, and thereby to open the valve and admit steam to the ejector. To prevent this action a spring-latch, h, is provided, which serves to lock the lever f and hold it back against the pressure of its spring.

E represents an air-chamber attached to the 20 wall of the cab or other suitable point, and is provided with a diaphragm, O, on one side of which is an air-chamber having communication with the brake-pipe B' through the tube B³ and B².

25 To the diaphragm O is secured a piston-rod, k, having a spring, i, bearing against a collar on the rod and against the wall of the diaphragm-shell, the effect of which is to propel it in an opposite direction to that in which the vacuum 30 acts.

To the rod k is attached a lever, l, suitably fulcrumed, which serves to operate the retaining-latch, whereby the hand-lever for turning on the steam to the ejector A is controlled. By 35 this arrangement, when air is admitted to the pipe B' it will also be admitted to the pipe B³, leading to the diaphragm-chamber, destroying the vacuum therein, when the spring i will be released from pressure, when it will expand, 40 causing the lever l to throw the retaining-latch h into action and allow of the steam-valve of the ejector A to be turned on, as has been set forth. This automatic device for operating the valve does not interfere with its use under 45 ordinary circumstances, the pin of the tail-extension piece of the hand-lever working freely within the slotted link, which latter is allowed for this purpose a horizontal vibratory movement upon its pivotal point.

50 The outward movement of the rod attached to the diaphragm O may be employed to set a steam-whistle or other alarm in action, for the purpose of calling the attention of the engineer to the brakes.

55 The brake-pipes A' and B' have, under certain conditions, communication with each other and with a reservoir and flexible vessels under each car of the train. In ordinary use the brakes are applied by creating a vacuum in 60 the pipe A' and the flexible vessels by the ejector A, the brake-pipe B' and the reservoir being cut off by a valve device. In the brake-pipe B' a vacuum is constantly maintained by the continuously-acting ejector B, and which 65 also exhausts the reservoirs and closes the valves connecting the brake-pipes A' and B'.

When, however, a more instantaneous action of the brakes is required than that furnished by the employment of the ejector A and pipe A', air is admitted to the exhausted brake-pipe 70 B', the effect of which is to open communication with the brake-pipe A' and the flexible vessels and reservoirs under the several cars, and at the same time air being admitted to the flexible chamber E of the automatic valve device 75 causes the diaphragm to move and sets the ejector A in action by turning on its steam-valve, thereby re-enforcing the vacuum in the pipe A', already established by having been connected with the reservoirs located on the 80 cars of the train.

The ejector B is made of comparatively small size, and a jet of steam is kept constantly blowing through it sufficient to keep the brake-pipe B' and the reservoirs in a constant state of exhaustion. These ejectors A and B may be 85 made to operate independently or in conjunction with each other, as also are the brake-pipes A' and B'.

In order to show to the engineer the degree of 90 exhaustion in the two brake-pipes, I provide a compound Bourdon gage with two index-hands and two scales upon the same dial. These index-hands are operated by sector-racks actuated by the motions of the gage-tubes, with 95 which they are respectively connected. Thus the motions of the two hands over their respective graduated scales upon the same dial will show at a glance the state of exhaustion in the two vacuum-brake pipes. I can also use 100 a single gage, which may be alternately put into communication with the pipes A' and B' by a double-ended self-acting check-valve at the point of junction of the tubes. This arrangement is shown in Fig. 7.

Having described my invention, what I claim is—

1. The ejectors A and B, the former having communication with the double line of pipes A' B', and the latter with brake-pipe B', substantially as and for the purpose set forth.

2. The ejectors A and B, arranged for operation substantially as set forth, the ejector A being adapted for intermittent and the ejector B for continuous action, for the purposes described.

3. The ejectors A and B, of comparatively different sizes and capacities, as herein described, in combination with a double line of brake-pipes, substantially as and for the purpose set forth.

4. The controlling-valve of the ejector A, adapted to be automatically operated upon the admission of air to the brake-pipe B', substantially as and for the purpose set forth.

5. An automatically-operating valve device, consisting of lever D d', slotted link e, lever f and its spring, catch h, with a diaphragm, O, and its spring, whereby, upon admission of air to the pipe B', the ejector of the pipe A' is 125 set in action, substantially as set forth.

6. A diaphragm connected to the pipe B',

and arranged so that on air being admitted to said pipe the controlling-valve of the ejector A will be automatically turned on, for the purposes set forth.

5 7. A retaining-catch for holding the lever *g* against the drag of its spring, in combination with an automatic device for setting the catch in action, whereby the steam-valve of the ejector A is turned on upon air being admitted to the brake-pipe B'.

8. The combination of two ejectors, A and B, substantially as described, with a double line of pipes, A' and B', and the valve *b'*, whereby the ejector A may have but a single 15 connection with its ejector, substantially as and for the purpose specified.

9. The combination of two ejectors, A and B, of comparatively different sizes and capaci-

ties, as herein set forth, and a double line of brake-pipes, A' and B', the ejector B of which 20 is kept in continuous action to maintain a constant vacuum in the brake-pipe B', substantially as set forth.

10. The combination of the ejectors A and B and brake-pipes A' and B', in which the application of the brakes is effected ordinarily by the ejector A and pipe A', and in cases of emergency by the admission of air to the brake-pipe B' and the action of ejector A, substantially as herein set forth. 25

In testimony whereof I affix my signature in presence of two witnesses.

F. W. EAMES.
